[57] CLAIM

The ornamental design for a through glass antenna, as
shown.

DESCRIPTION

FIG. 1 is a top plan view of a through glass antenna
showing my new design;

FIG. 2 is a right side elevational view thereof;

FIG. 3 is a front elevational view thereof;

FIG. 4 is a rear elevational view thereof;

FIG. 5 is a bottom plan view thereof; and

FIG. 6 is a left side elevational view thereof.

The broken line showings are for environmental pur-
poses only and form no part of the claimed design.

*Fig. 4.**Fig. 5.**Fig. 6.*
